UNITED STATES PATENT OFFICE.

SAMPSON BACHRACH, OF CHICAGO, ILLINOIS.

DESIGN FOR A DISPLAY-CABINET.

40,762.

Specification for Design.

Patented July 12, 1910.

Application filed April 21, 1910. Serial No. 556,907. Term of patent 14 years.

To all whom it may concern:

Be it known that I, SAMPSON BACHRACH, a citizen of the United States, residing at Chicago, in the county of Cook and State of Illinois, have invented a new, original, and ornamental Design for Display-Cabinets, of which the following is a specification, reference being had to the accompanying drawing, forming a part hereof, which shows a perspective view of said design.

I claim:

The ornamental design for a display cabinet, as shown.

SAMPSON BACHRACH.
